UNITED STATES PATENT OFFICE.

ALBERT M. PIGEON, OF PHILADELPHIA, PENNSYLVANIA, ASSIGNOR TO WILDMAN MFG. CO., OF NORRISTOWN, PENNSYLVANIA, A CORPORATION OF PENNSYLVANIA.

CIRCULAR-KNITTING MACHINE.

Application filed October 25, 1912. Serial No. 727,700.

The invention relates more particularly to knitting machines of the cylinder type, wherein the needles and supporting cylinder may be rotated for circular knitting or oscillated at certain intervals, if desired.

An object of the invention is to provide a yarn feed or yarn guide with means whereby the same may be automatically rendered inoperative, and the yarn fed thereby cut 10 from the web and the free end clamped and held until said yarn feed is again automatically rendered effective.

A further object of the invention is to provide a yarn feed of the above character, 15 wherein a plurality of yarns may be independently controlled and independently fed to the knitting needles, or rendered inoperative and each yarn cut from the web and clamped and held until it is desired to again 20 feed the yarn to the knitting needles.

A further object of the invention is to provide means for feeding a splicing yarn to the knitting needles, for reenforcing a portion only of the knitted web during circular, 25 or round and round knitting, which yarn feed is so disposed that the yarn may be led from a feeding-in point, substantially diametrically opposite the knitting point in the cylinder.

30 A still further object of the invention is to provide means for throwing down one series of the needles at a point opposite the knitting point in the cylinder during the feeding-in of the splicing yarn, so that said splicing yarn is brought into contact only 35 with the needles by which said yarn is looped.

These and other objects will in part be 40 obvious, and will in part be hereinafter more fully described.

In the drawings, which show by way of illustration one embodiment of the invention,

Fig. I, is a plan view of a portion of a 45 knitting machine having my improvements applied thereto.

Fig. II, is a side view of the upper portion of said machine.

Fig. III, is a similar view taken from the 50 other side of the machine.

Fig. IV, is a vertical section on line IV, 55 IV, in Fig. I, through the needle cylinder, the supporting frame therefor and the im-

mediate mechanism for driving the cylinder.

Fig. V is a horizontal section on line V, 55 V, of Fig. III, showing the mechanism for operating the raising and lowering cams in plan, also the pickers in plan, and the cam for depressing certain of the needles to prevent the same from engaging the auxiliary 60 splicing yarn.

Fig. VI, is a diagrammatic view, showing the cams for engaging the needle butts during the knitting and also the pickers used 65 during widening and narrowing;

Fig. VII, is a perspective view showing the sections of the pattern drum for controlling the yarn feeding devices, the auxiliary 70 splicing yarn and the ratchet wheel for turning the drum.

Fig. VIII, is a vertical sectional view on line VIII, VIII, of Fig. I, through the pattern drum for the yarn feeding devices, and also through the supporting members therefor.

Fig. IX, is a perspective view showing the 75 yarn cutting device, the guiding member for the yarn, and the clamping finger for engaging and holding the cut end of the yarn, one yarn being held by the clamp and the second yarn being carried into said clamping and cutting devices.

Fig. X, is a similar view, showing a yarn 80 held by the clamping device and another yarn thrown into effective knitting position.

Fig. XI is a view similar to Fig. X, showing the yarn being withdrawn from the clamping finger.

Fig. XII, is a perspective view of the upper end of the needle cylinder showing 90 the needles, the main yarn feed, the auxiliary splicing yarn feed, and the relative position of these parts.

Fig. XIII, is a sectional view on line XIII, XIII, of Fig. I, through the upper 95 end of the needle cylinder, showing, my improved beard depresser.

Fig. XIV, shows a development of the pattern drum for controlling the yarn feeds.

In the present embodiment of the invention, the machine consists generally in a 100 needle cylinder, which is provided with a plurality of spring beard needles, the beards of which are depressed by suitable beard depressers at the proper time to shed the yarn 105 loops therefrom. Each needle is provided

with a beard depresser, and said beard depressers are rocked by suitable cams, so as to engage the beards and press the same at the proper time for the shedding of the loop. 5 As soon as the beard depresser passes the cam, it is automatically withdrawn therefrom. The yarn is fed to the needles by a plurality of yarn feeding devices, which are controlled by a pattern drum operated from 10 the main pattern mechanism, so that one or more of said yarn feeding devices may be rendered effective, or inoperative, as desired. The invention contemplates further a yarn cutting and clamping device, which is so 15 constructed that when a yarn feeding device is rendered inoperative, the yarn will be drawn into a clamping device and then into a cutter, where it is cut between the web and the clamping device, so that said yarn is entirely severed from the web and the free end thereof is held by said clamping device. This clamping and cutting device is also so 20 constructed that when a yarn feeding device is thrown into operation, the yarn will be drawn from the clamping device in such a way as not to disturb other yarns clamped thereby. The invention further contemplates an auxiliary splicing yarn feed which is so disposed as to direct the yarn to the 25 needles from a point substantially opposite the knitting point in the needle cylinder. Co-operating with this splicing yarn feed is a cam which lowers all of the long butt needles in a region opposite the knitting point, so 30 that the splicing yarn will be positioned so as to contact with the first needle in the short butt series, and said needles position the yarn at the knitting point so that it is properly engaged by the needle. This 35 positioning of the auxiliary splicing yarn feed is also such that the yarn is drawn about the last needle of the short butt series and between said needle and the first needle of the long butt series, before said long butt 40 needle is raised, thereby insuring the termination of the feeding-in of the auxiliary splicing yarn in certain portions of the wales of the web.

Referring more in detail to the drawings, 45 my improved knitting machine consists of a needle cylinder 1, which is provided with spring beard needles 2, located in the channels formed in the needle cylinder and attached to the needle jacks 3. This needle cylinder 1, is mounted on a supporting bed 4. A gear 5, is attached to the needle cylinder and meshes with a gear 6, mounted in the main frame, and actuated from a bevel gear 7, which is attached thereto. The 50 bevel gear 7, may be rotated for rotating the needle cylinder, or may be oscillated for oscillating the needle cylinder. The needle cylinder is supported in the main frame and connected to the gear 6, so that it may be 55 raised and lowered for the fashioning of the

web. My improved knitting machine is preferably adapted for knitting stockings, and the needles are, therefore, divided into two series, as is usual in this type of machine, and in one of the series the needle jacks are formed with long butts, while in the other series the needle jacks are formed with short butts. 70

When the heel and toe pockets are being knit, the long butt needles are raised to idle 75 position. This is accomplished in my present invention by a raising cam 8, and said needles are again depressed, so as to bring them into active position by a depressing cam 9. The cams 8, and 9, are independently mounted on a vertical supporting stud 10. The cam 8, is carried by a lever 11, which extends beyond the pivotal support, and is provided with a pin 12, adapted to be engaged by an arm 13, carried by a supporting member 14, which is moved laterally when the clutch is shifted for changing the movement of the needle cylinder from rotation to oscillation, and vice versa. A spring 15, carried by the lever 11, normally 80 presses the cam 8, so that it is brought into position to engage the long butts on the needle jacks. When the supporting member 14, is moved away from the needle cylinder, the cam 8, will be brought into position, so 85 as to engage the needles having long butts, and said needles will be raised to idle position. The cam 9, is carried by a supporting arm 16, which is also freely mounted on the vertical stud 10, and a spring attached to the arm normally swings the cam 9, into the path of movement of the long butts on the needle jacks. The supporting member 14, carries a second arm 17, which is formed with a slot 18, adapted to engage a stud or 90 pin 19, carried by the arm 16. When this supporting member 14, is moved away from the needle cylinder, so as to release the cam 8, the end of the slot 18, will engage the stud 19, and move the cam 9, out of the path 95 of travel of the long butts on the needle jacks. It will thus be seen that I have provided means whereby independently mounted cams may be alternately thrown 100 into effective operation, either for raising 110 the long butt needles to idle position, or for depressing the long butt needles to active position. This cam controlling mechanism forms no part of my present invention, but is shown described and claimed in my Patent 105 No. 1,266,044, dated May 14, 1918. 110

Co-operating with the active series of needles during the knitting of the heel and toe pockets, for narrowing the stocking, are pickers 20, and 21. These pickers operate 115 in the usual way to render the advanced needle of the active series idle during the oscillation of the cylinder in either direction. When the cylinder is rotated for circular knitting, the picker 20, should be moved 120

- out of active position. This is accomplished by a third arm 22, mounted on the supporting member 14, which engages a pin 23, on the shank of the picker 20, and turns said picker to idle position. When the cam 8, is thrown out of action and the depressing cam 9, thrown into action, so as to bring the long butt needles into active position, the picker 20, is moved to inoperative position.
- 10 The widening of the stocking at the heel and toe pockets is accomplished by the pickers 24, and 25. Each of these widening pickers is mounted for independent movement on an arm which has a universal connection with the support therefor. The pickers are moved to inoperative position during circular knitting by a bar 26, which is carried by a lever 27. The lever 27, is automatically shifted by the parts which are moved for bringing about the rotation of the cylinder.
- 15 Mounted in the supporting ring at the top of the needle cylinder are fabric supporting members 28, see Figs. IV and XIII. These fabric supporting members are provided with yarn supports 29. The fabric supporting members are independent of each other and extend between the needles. Said fabric supporting members are independently moved radially of the needle cylinder
- 20 by suitable cams. The inner ends of the yarn supporters are preferably beveled, and these yarn supporters are timed so as to be withdrawn after the yarn has passed underneath the spring beards of the needles. The
- 25 yarn supports form no part of the present invention, but are shown, described and claimed in my Patent No. 1,266,044, dated May 14, 1918, and further description thereof herein is not thought necessary.
- 30 The spring beards are closed so as to allow the yarn loops to be shed from the needles by beard depressers 30, see Fig. XIII. There is a beard depresser for each needle, and said beard depresser is formed with a shank, which is located between the ribs of the needle cylinder and outside of the needle.
- 35 Said depresser at its inner edge is curved so as to form a high point 31. A coil spring 32, is located in a groove formed in the ribs of the needle cylinder and is adapted to engage a V-shaped notch 33, in each needle depresser. This spring rocks the beard depresser about its high point 31, so as to hold the lower end of the beard depresser moved
- 40 inwardly toward the needle cylinder. The upper end of the beard depresser is formed with a beard engaging face 34. The front face of the beard depresser is preferably widened so as to practically fill the space
- 45 between the yarn supporting members 28, and thereby insure said beard depresser engaging the beard of the needle. When the lower end of the beard depresser is forced inwardly by the spring 32, said beard depresser will rock about the high point 31,
- 50 which withdraws the face 34, of the beard depresser away from the needle, so as to permit the yarn to be fed between the beard depresser and the beard of the needle. This beard depresser has no vertical movement, as has been customary heretofore, but is rocked solely about this high point 31. Mounted on the stationary frame at the top of the needle cylinder, are cams 35, and 36, see Figs. I and XIII. These cams are positioned so as to engage the beard depressers as they pass thereby and force the upper end of the beard depressers toward the needles, so as to cause the face 34, of each beard depresser to engage the spring beard and close the same so that the yarn may be shed over said spring beard. As soon as the beard depresser passes the cams, the coil spring 32, will at once cause the beard depresser to release the needles. I have shown two cams for engaging the beard depressers, one of which becomes operative in shedding the yarn loops when the cylinder is moving in one direction, and the other of which becomes operative in the shedding of the yarn loops when the cylinder is oscillating in the opposite direction. These beard depressers are shown, described and claimed in my Patent No. 1,247,324, dated November 20, 1917.
- 55 I have provided means for feeding to the knitting needles either simultaneously or alternately, several knitting yarns. Said yarn-feeding mechanism consists, as herein shown, of four yarn-feeding fingers 37, 38, 39 and 40. Each of these yarn-feeding fingers is formed with a yarn guide 41, at its free end, through which the yarn passes to the knitting needles. Each finger is also mounted on a supporting arm 42. These supporting arms are carried by a supporting rod 43, and are so mounted as to move independently of one another. Each arm is provided with an adjustable cam lug 44. This lug is slotted as at 45, and is held in various adjusted positions by a screw 46. By unfastening the screw the lug may be slid longitudinally of the arm 42, and the distance of the lug from the pivotal point of the arm varied.
- 60 The cam lugs 44, of the several arms supporting yarn-feeding fingers, bear on a pattern drum 47. A rearwardly extending arm 48, is rigidly carried by the brackets supporting the rod 43, and the drum 47. On said arm 48, I have placed a series of springs 49, one for each arm 42. These springs at their free ends bear on the arms, and normally press the cam lugs 44, against the pattern drum.
- 65 This pattern drum 47, as shown in Figs. VII, and VIII, is provided with a series of spaced projecting segments 50, which are of different lengths and so spaced relative to one another as to secure the proper throw-

ing in and out of yarn-feeding fingers controlled thereby. That is to say, the cam lug 44, rests on this segment, and as the drum is turned, said lug will drop off the end of the 5 segment. When the cam lug 44, rests on the outer face of the segment, the yarn-feeding finger is raised to inoperative position, while when said cam lug 44, is off the segment, then the yarn-feeding finger is lowered into 10 active position. This drum 47, is mounted to rotate freely on a supporting stud 51, carried by the bracket supporting the yarn-feeding devices, and the drum is rotated by a ratchet wheel 52.

15 A lever 53, is oscillated by a link 54, which is moved by the main pattern mechanism of the knitting machine. Said lever 53, is pivoted to swing about the axis of the drum. At the outer end of said lever is a spring- 20 pressed pawl 55, which is adapted to engage the teeth of the ratchet wheel 52. When the link 54, is reciprocated, the lever 53 will be oscillated and the spring-pressed pawl 55, will engage the ratchet wheel and turn it 25 step by step.

A stop screw 56, limits the upward throw of the free end of the lever 53. Said stop screw engages the supporting bracket for the drum. This pattern drum is rotated at times 30 by the main pattern mechanism, so as to cause the yarn-feeding fingers to be thrown into or out of action in accordance with the pattern segments carried by the drum.

35 As shown in Fig. I, of the drawings, the yarn-feeding finger 40, is in action while the other yarn-feeding fingers are out of action. This yarn-feeding finger may be used for feeding a yarn during the knitting of the garter top of a stocking.

40 In Fig. XIV, I have shown the development of the pattern drum for the yarn-feeding fingers and indicated the different positions of the drum by the Figures I to 9 inclusive, and the broken lines indicated by 45 these figures. I have also indicated by the arrow the direction of movement of the drum.

The yarn finger 40, co-operates with the 50 segments *a*, while the yarn fingers 39, 38, and 37, co-operate respectively with the segments *b*, *c*, and *d*. When the pattern drum is positioned so that the section indicated by the broken line 1, is engaged by the cam lugs, the finger 40, will be depressed as the segment *a* at this point terminates. Upon further turning of the drum one tooth, so as to bring the part indicated by the broken line 2, underneath the cam lugs, the finger 39 55 carrying the yarn for knitting the leg portion of the stocking, will be thrown into action, and after said finger is thrown into action, the finger 40, will be raised to inoperative position. This is accomplished by reason of the fact that the broken away 60 part or space in the projecting segment *a*

overlaps the broken away part or space in the projecting segment *b*.

When the part indicated by the broken line 3, is brought underneath the cam lugs 44, the finger 38, is thrown into action. The finger 39, remains in action until after the finger 38, is brought into action, after which said finger 39, is moved out of action. The 70 yarn guided by the finger 38, may be used for the ankle of the stocking. This finger 75 remains in action until the part of the drum indicated by the broken line 7, comes underneath the cam lugs 44, at which time the finger 37, is brought into action. The finger 80 85 85 is supplied with a splicing yarn in addition to the main yarn and these two yarns are fed simultaneously for the knitting of the heel pocket. Thereafter the yarn guided by the finger 38, may be again brought into action for knitting the sole of the stocking, when the portion of the drum indicated by the broken line 8, is underneath the cam lugs 44, and following this, the double yarn carried by the finger 37, is again brought 90 into action for knitting the toe pocket. 95

Prior to my invention, it has been customary to float the yarns of the fingers which are inoperative. It is impractical to float more than one yarn during the circular knitting, as the yarns become very much twisted. 95 The present invention contemplates, therefore, a yarn cutter and clamping device, whereby the yarn of the finger which is thrown to inoperative position may be severed from the web, and the end of the yarn 100 clamped and held until said yarn guide is again thrown into action. This yarn-cutting and clamping device consists of a supporting plate 57, which is carried by a bracket 58, formed on the end of a long arm 59, 105 rigidly fixed to the rod 43, by a set screw 61. This arm 59, extends over the needle cylinder, and the bracket 58, depends therefrom, so that the supporting plate 57, is held at a point below the upper ends of the needles in the needle cylinder, and at a point substantially in the plane of the fabric-supporting members. Said plate is curved 110 as at 62, to conform to the inner surface of the needles, and is slightly spaced therefrom. 115

The plate is also provided with a slot 63, terminating in an eye 64. This slot provides a tongue 64^a extending from the outside of the plate 57 in the direction toward the yarn-feeding fingers as appears from Fig. I. The tongue 64^a, as shown by the perspective views Figs. IX, X and XI, is curved upward at its extremity from the plane of the plate 57, so that a yarn from a feeding finger in the active position is carried by the movement 120 of the cylinder under the tongue 64^a, while the cut end lies between the slot 63 and the clamp 64 on top of the plate 57, as shown in Figs. X and XI. When the yarn-feeding finger is raised to the inactive position, this 125 130

yarn is held above the extremity of the tongue 64^a. The slot 63 increases in width toward its open end, so as to form a widened receiving mouth for the yarn when the 5 same is thrown into action.

The yarn clamp consists, as herein shown, of a spring finger 65, which is formed of a spring wire fixedly attached to the supporting bracket 58, by a screw 66, Fig. 1. The 10 wire is coiled, and is bent so as to be pressed against the supporting plate 57. Said wire is preferably formed with a curled end 67, which is slightly raised from the plate, so as to allow the yarn to be drawn underneath 15 said clamping finger.

A cutter 69, is also carried by the supporting bracket, and is held in fixed position relative thereto. Said cutter is provided with a cutting edge 70, which is spaced above 20 the supporting plate 57, so that the yarn may be drawn underneath the cutting edge. This cutting edge extends downwardly into a slot in the supporting plate, so that when the yarn is drawn underneath the cutter, it 25 will contact with the cutting edge thereof, and the yarn will be severed. Said cutter 69, is preferably set at an angle to the direction of movement of the cylinder, to aid in cutting the yarn.

In Fig. IX, I have shown a yarn 71, clamped by the yarn-clamping finger, and a yarn 72, being drawn into said clamp. The point 73, indicates the place where the 30 yarn is attached to the web when its yarn feeding finger is thrown to inoperative position and the yarn withdrawn from knitting position relative to the needles. This point 73, is, therefore, a traveling point moving 35 along the outer edge of the supporting plate 57, in the direction of the arrow in said figure. As the cylinder continues to rotate, the yarn will be drawn underneath the 40 clamping finger 65, and against the cutting edge of the cutter 69, where it will be severed.

The free end of the yarn extending to the 45 yarn feeding finger therefor, is clamped by the clamping finger, while the yarn is severed between the clamping finger and the knitted web.

When it is desired to throw a yarn feeding finger into action, it is moved downward, as described above. The yarn between the clamping finger and the yarn guide will be 50 caught by the needles, and the point 74, in Fig. X indicates the place where the yarn is knitted into the web. This point travels 55 along the outer edge of the supporting plate 57, in the same manner as described in connection with Fig. XI. The yarn will be 60 drawn underneath the outer extremity of tongue 64^a of the plate 57 and into the receiving mouth of the slot 63. As the yarn moves along the slot, it will be brought to 65 the eye 64, therein, and a further pull on the

yarn as the cylinder rotates, will draw the 70 yarn from underneath the clamping finger, and out through the eye 64.

It is to be noted that this pull on the yarn in pulling it from the clamping finger, is 75 in the same direction as the yarn is placed under the clamping finger, and, therefore, the pulling of one yarn out of the clamping finger will not disturb the other yarns held by the clamping fingers, but, on the contrary, 80 will tend to pull said yarns well underneath said clamping finger.

This pull on the yarn, in view of the position of the eye 64, relative to the cutting knife, will also cause the yarn to be pulled 85 backwards from under the knife, thereby keeping the knife clean.

From the above description, it will be apparent that I have provided a yarn-clamping and cutting device which will automatically 90 operate to clamp the yarn when a yarn guide is thrown to inoperative position, and cut the yarn between said clamp and the web, so that the web is entirely free of the yarn. Furthermore, when a yarn-feeding finger is 95 thrown into action, the clamping device readily releases the yarn, so that it may be entirely free from the clamping device.

Furthermore, this clamping and cutting 100 of the yarn or the releasing of the yarn, operates in precisely the same manner, whether one yarn is clamped and cut, or whether several yarns are cut and held by the clamping device.

The supporting arm 59, for the yarn-cutting and clamping device may be raised, if desired, by swinging the supporting rod 43, therefor. Said rod 43, carries a plate 75, and a pin 76, carried by the supporting bracket for the arm 59, is adapted to engage 105 openings formed in the plate for holding the yarn feeding fingers together with the arm supporting the yarn-cutting and clamping device either in operative or inoperative position, so that when necessary this entire 110 mechanism may be thrown back to afford access to the needle cylinder.

Another feature of my invention consists in a yarn feeding device for feeding an auxiliary splicing yarn during the knitting of a stocking, so as to reinforce such portions of the stocking as may be desired. This auxiliary splicing yarn feed consists of a yarn-feeding finger 77, having a yarn guide 78, at the outer end thereof. This yarn 115 feeding finger 77, is mounted on an arm 42, similar to that above described, and is provided with a cam lug 44, which cooperates with the pattern drum 47. The pattern segments *e* shown in Figs. VII and XIV, control the feeding of this auxiliary splicing 120 yarn. It is desirable in the knitting of a stocking to introduce a reinforcing yarn at the lower part of the ankle portion of the stocking, at the back half of the stocking; 125 130

also for reenforcing the sole of the stocking between the heel and toe pockets. These pattern segments *e* on the drum 47, are therefore, so constructed as to terminate and provide suitable spaces so that the slicing yarn guide may be lowered into operative position at the proper time during the knitting of the stocking. It will be apparent from Fig. XIV, that the space at the broken line 6, wherein the auxiliary splicing yarn is thrown into action, occurs while the fashioning yarn guided by finger 38, is fed to the needles and prior to the throwing in of the yarns for the knitting of the heel pocket. When the yarns for the knitting of the heel pockets are thrown into action, the auxiliary splicing yarn is thrown out of action, and when the yarn fed by finger 38, for the knitting of the foot of the stocking is again thrown into action, the auxiliary splicing yarn is also thrown into action.

This auxiliary splicing yarn guide, as shown in Fig. I, extends over the cylinder to a point substantially diametrically opposite the knitting point of the needles in the cylinder. This splicing yarn is floated during the knitting of the tubular web until the point is reached where it is desired to knit with the splicing yarn. A curved guide 79, is formed with a supporting shank 80, by which it is attached to the supporting ring at the top of the needle cylinder. This guide 79, is inclined downwardly into the needle cylinder, and holds the splicing yarn depressed centrally of the cylinder. Co-operating with the auxiliary splicing yarn feed is a cam 81, see Figs. II, V and VI. This cam is fixed to the supporting frame and is positioned so as to engage the long butt needles, that is, the needle jacks having the long butts, and depresses the corresponding needles, as shown in Fig. XII, to a point so that these needles will pass underneath the auxiliary splicing yarn. The auxiliary splicing yarn is thrown into action while the cylinder is rotating, and, therefore, the cam 8, does not engage the long butts, as it is in inoperative position during circular knitting. These long butt needles are, however, raised just prior to reaching the stitching cams, so that said long butt needles become active for knitting with the main knitting yarn. The operation of this auxiliary splicing yarn feed will be apparent from Fig. XII of the drawing. The long butt needles are rendered inactive by the cam 81, as above noted, as they pass the auxiliary splicing yarn. The first needle in the short butt series will, therefore, engage the splicing yarn at a point below the beard of the needle. As the cylinder continues to rotate, the auxiliary splicing yarn will be laid against the outer face of the shanks of the short butt needles, and when the needles reach the knitting cams, said yarn will be

knit with the main yarn supplied to said needles. As the last needle indicated at 82, in Fig. XII, reaches the point indicated in this figure the yarn will be drawn around the shank, and the position of the guide for the auxiliary splicing yarn is such that said yarn will be passed between the needle 82, which is the last needle of the short butt series, and the needle 83, which is the first needle of the long butt series. When the needles having the long butts are raised to active position, the auxiliary splicing yarn will be at the rear thereof, and will not be taken by them. As the cylinder rotates, the auxiliary splicing yarn will be carried diametrically across the cylinder, as indicated by the dotted line 84, in Fig. XII. The needle 85, represents the first needle of the short butt series, and as the cylinder rotates, all of the long butt series in advance thereof will be depressed so that the auxiliary splicing yarn will be wrapped around the shank of this needle 85. By this positioning of the auxiliary splicing yarn feed, and the throwing down of the long butt needles, I am able to cause the splicing yarn to be looped definitely in the same wale of the knitted web. When the auxiliary splicing yarn is thrown out of action by the upward movement of the guiding finger therefor, said yarn is moved out of range of the needles and will float until again brought into action. While I have shown the guide for the splicing yarn as substantially opposite the knitting point, it is obvious that it may be otherwise positioned, so long as it is properly related to the needles to hold its yarn so as to be engaged by the first needle in the short butt series, and also to be carried between the last needle of the short butt series and the first needle of the long butt series.

It is thought the operation of my device will be apparent from the above description. In the knitting of a stocking, a certain desired yarn may be caused to be engaged by the needles during the forming of the garter top. After this is completed, this yarn may be thrown out of action, the yarn clamped and severed from the web. Prior to the throwing out of action of this yarn, a second yarn may be thrown into action for knitting the leg of the stocking. When the ankle of the stocking is reached, the yarn for knitting the leg is withdrawn and another yarn may be thrown into action together with the auxiliary splicing yarn for reenforcing the rear half of the stocking. During the rotation of the needle cylinder, the long butt needles which knit the front half of the stocking are depressed so as to pass beneath the auxiliary splicing yarn feed and said long butt series of needles are brought into active knitting range with the main yarn at the knitting point. By this feeding of the auxiliary

130

- splicing yarn, from a point at the opposite side of the needle cylinder from the knitting point to selected needles at a higher level than the other needles, the auxiliary splicing 60
yarn may be caused to engage definitely with certain needles, and may be caused to guide the yarn without any movements of the auxiliary yarn feeding guide toward and from the cylinder, as is usual where splicing yarn 65
is fed to the needles passing the guide at the same level. When the point is reached for the knitting of the heel pocket, two yarns fed from a single feed may be thrown simultaneously into operation, and the yarns used 70
10 for knitting the ankle of the stocking, caught by the yarn clamp and the ends thereof severed from the knitted web. The fashioning yarn (the yarn used in knitting the ankle) may again be used during the knitting 75
20 of the foot portion of the stocking after the heel pocket is finished, and the auxiliary splicing yarn may at the same time be again thrown into action for reenforcing the sole of the foot portion of the stocking. When 80
25 the toe pocket is reached, the double yarn (same as used for the heel) for knitting the same may be again thrown into action and the yarns for knitting the foot thrown out of action. The clamping of the yarn occurs 85
30 before the yarn is cut, and after the yarn is clamped, it is cut between the clamping finger and the web. The clamping device is so positioned and constructed that the yarn is drawn out of the clamping device in the 90
35 same direction in which it is placed in the clamping device, and, therefore, the yarns held by the clamping finger are not disturbed.
- By the use of the several independent feeds 40 for the threads, as herein shown, I am enabled to use threads of different qualities or weights for the different portions of the stockings. For example, the garter top may be knit of ordinary yarn of a heavy weight, 45 while the leg of the stocking may be knit of silk. When the ankle is reached another 50
55
yarn may be substituted together with a reinforcing yarn, and this is also true of the foot portion of the stocking. The heel and toe pockets may also, if desired, be knit of still heavier yarn or yarn of different quality from that used in other portions of the stocking.
- In this manner the exposed portions of 60
55
a stocking may be knit of silk and by reason of the auxiliary splicing feed, reinforced at certain parts with the same material, while the foot portions may be reinforced with material of cheaper quality.
- The spring beards of the needles are 65
60
readily controlled by the beard depressers, which are simply rocked without being moved endwise by a stationary cam, which engages the beard depressers at the proper time for closing the beards of the needles.
- Not only are these beard depressers simple in construction and action, but they may be readily removed from the needle cylinder without removing the supporting ring at the top of the cylinder, merely by pulling the 70
depressor upwardly out of the needle slot in the cylinder. The notch in which the coil spring rests is V-shaped and, therefore, said beard depresser may be readily removed. The lower end of the beard depresser is also 75
tapered so that it may be readily inserted merely by pressure, as the tapered end will engage the coil spring and allow the lower end of the beard depresser to pass the same, so that the spring may slip into the notch 80
in said depresser.
- While I have herein shown, by way of illustration, one embodiment of the invention, i. e., in a knitting machine of the spring beard type, and have indicated the preferred means for positioning the groups of needles with relation to the auxiliary yarn, it is obvious that the invention is not necessarily restricted to that class of knitting machines or to the particular positioning means 85
90
95
specified.
- It is obvious that minor changes in the details of construction and the arrangement of parts may be made without departing from the spirit of the invention, as set forth in the appended claims.
- Having thus described my invention I claim:
1. In a knitting machine, the combination of a needle cylinder, a series of needles carried thereby, a yarn feeding device, means whereby said yarn feeding device may be rendered inoperative, and a yarn clamping and cutting device, said cutting device being located between the clamping device and the web, and means for positively guiding the yarn from contact with the cutter when the yarn feeding device is thrown into operation and for pulling the yarn from the clamping device, the yarn being removed first from the clamping device and then from the cutter. 100
105
  2. In a knitting machine, the combination of a needle cylinder, a series of spring beard needles carried thereby, a plurality of yarn feeding devices, means for independently rendering said yarn feeding devices operative or inoperative, a yarn clamping and cutting device including a supporting plate, a clamping finger for yieldingly clamping the yarn against the plate, a stationary cutter for cutting the yarn between the clamping finger and the web, and means for positively guiding the yarn from contact with the cutter when the yarn feeding device is thrown into operation and for pulling the yarn from the clamping device, the yarn being removed first from the clamping device and then from the cutter. 110
115
120
  3. In a knitting machine, the combination 125
130

- of a needle cylinder, a series of spring beard needles carried thereby, a plurality of yarn-feeding devices, means for independently rendering said yarn-feeding devices operative or inoperative, a yarn-clamping and cutting device including a supporting plate, a clamping finger for yieldingly clamping the yarns against said plate, and a stationary cutter for cutting the yarn between the clamping finger and the web, said supporting plate having a slot formed therein into which the yarn is drawn when thrown into action, said slot terminating at a point between the cutting knife and the clamp whereby said yarn may be drawn from the clamping finger by a movement in the same direction in which the yarn is placed underneath said clamping finger.
4. In a knitting machine, the combination of a needle cylinder, a series of spring beard needles carried thereby, a plurality of yarn-feeding fingers for guiding independent yarns, a pattern drum having pattern segments thereon for throwing said fingers into and out of action, means for moving said drum step by step, a yarn-clamping and cutting device for clamping and holding the ends of the yarn of the idle yarn-feeding fingers and for severing said yarns from the knitted web and means for positively guiding the yarn from contact with the cutter when the yarn feeding fingers are thrown into operation and for pulling the yarn from the clamping device, the yarns being removed first from the clamping device and then from the cutter.
5. In combination in a circular knitting machine, a cylinder, needles, a horizontal plate within the needle circle, a yielding clamping finger resting thereon, said plate having a finger projecting therefrom in a direction opposite the movement of the cylinder, and having an opening in rear of the clamp to receive the yarn, a cutting knife in rear of said bearing extending at right angles to the surface of the plate and with its cutting edge inclined in relation to said surface, substantially as described.
6. In a knitting machine, a needle cylinder; a series of needles carried thereby; means for feeding yarn to all of said needles during round and round knitting; said needles passing said yarn guide at a common level; means for feeding an auxiliary yarn at a different point from said first mentioned yarn feed; and means for positioning a selected group of needles at a level adapted to engage said auxiliary yarn and for positioning another selected group of needles at a level adapted to pass underneath said auxiliary yarn, said means for feeding the auxiliary yarn being so positioned relative to the first mentioned selected group of needles that the auxiliary yarn is drawn into engagement with and partially about the shank of the leading needle of said group, whereby the insertion of the auxiliary yarn at a definite point in the fabric is positively ensured.
7. In a knitting machine, a needle cylinder; a series of needles carried thereby; means for feeding yarn to all of said needles, during round and round knitting; a yarn guide for feeding an auxiliary yarn at a different point from said first mentioned yarn feed; means for moving said auxiliary yarn guide into and out of operative position for causing the auxiliary yarn to engage a selected group of needles, and for holding said yarn guide in fixed position, while feeding yarn to said selected group of needles for successive knitting rotations; means for positioning another selected group of needles, at a level whereby they pass underneath the auxiliary yarn, and means for returning said last mentioned group of needles to normal knitting position after passing the auxiliary yarn.
8. In a circular knitting machine, a needle cylinder; a series of needles carried thereby; a yarn guide for feeding yarn to all of said needles for circular knitting; a yarn guide for feeding an auxiliary or splicing yarn to a group of said needles, said yarn guide for the auxiliary or splicing yarn having an unvarying feeding position relative to the first mentioned yarn guide for successive rounds of knitting from margin to margin of the splicing area; means for depressing the needles that are outside of the splicing area below the splicing or auxiliary yarn feed level, so as to float the yarn across the circle of needles from side to side of the group of needles receiving the splicing or auxiliary yarn; and means for returning the depressed needles to normal knitting position after passing the splicing or auxiliary yarn.
9. In a knitting machine, the combination of a needle cylinder, a series of short butt needles, and a series of long butt needles, means for feeding a yarn to all of said needles, and means for feeding an auxiliary yarn to said short butt needles only, from a point substantially on the opposite side of the axis of the cylinder from the knitting point.
10. In a knitting machine, the combination of a needle cylinder, a series of short butt needles, and a series of long butt needles, means for feeding a yarn to all of said needles, means for feeding an auxiliary splicing yarn to said short butt needles only from a point substantially on the opposite side of the axis of the cylinder from the knitting point, and means for depressing said long butt needles, whereby they may be caused to pass underneath the splicing yarn.
11. In a knitting machine, the combina-

tion of a needle cylinder, a series of short butt needles, and a series of long butt needles, means for feeding a yarn to all of said needles, means for feeding an auxiliary splicing yarn to said short butt needles only from a point substantially on the opposite side of the axis of the cylinder from the knitting point, a cam for depressing the long butt needles, whereby the splicing yarn is drawn around the shank of the short butt needles, and means for raising the long butt needles for engaging the main knitting yarn at the knitting point.

12. In a knitting machine, the combination of a needle cylinder, a series of short butt needles, and a series of long butt needles, means for feeding a yarn to all of said needles, means for feeding an auxiliary splicing yarn to said short butt needles only from a point substantially on the opposite side of the axis of the cylinder from the knitting point, and a cam for depressing the long butt needles, whereby a splicing yarn is drawn around the shank of the first needle in the short butt series and pressed against the outer face of the short butt needles.

13. In a knitting machine, the combination of a needle cylinder, a series of short butt needles, and a series of long butt needles, means for feeding a yarn to all of said needles, means for feeding an auxiliary yarn to said short butt needles only from a point substantially on the opposite side of the axis of the cylinder from the knitting point, a cam for depressing the long butt needles, whereby said auxiliary yarn is drawn around the shank of the first needle in the short butt series and pressed against the outer face of the short butt needles, and means for raising the long butt needles after said auxiliary yarn has been drawn around the shank of the last needle in the short butt series and between said needle and the first needle in the long butt series.

14. In a knitting machine, the combination of a needle cylinder, a series of short butt needles, and a series of long butt needles, means for feeding a yarn to all of said needles, means for feeding an auxiliary splicing yarn to said short butt needles only from a point substantially on the opposite side of the axis of the cylinder from the knitting point, a cam for depressing the long butt needles, whereby a splicing yarn is drawn around the shank of the first needle in the short butt series and pressed against the outer face of the short butt needles, means for raising the long butt needles after said splicing yarn has been drawn around the shank of the last needle in the short butt series and between said needle and the first needle in the long butt series, and a yarn guide for engaging the splicing yarn between the yarn-feeding

device and the knitting point for holding the same depressed centrally of the needle cylinder.

15. In a knitting machine, the combination of a needle cylinder, a series of spring beard needles carried thereby, a plurality of yarn feeding devices, means for independently rendering said yarn feeding devices operative or inoperative, a stationary cutter for cutting the yarn between the yarn feeding device and the web, a supporting plate for said cutter, said supporting plate having a slot formed therein, and an eye, whereby said yarn may be drawn into the slot and pulled through the eye, and thus be drawn from the knife in the opposite direction to that in which the yarn was drawn against the knife.

16. In a knitting machine, the combination of a needle cylinder, a series of spring beard needles carried thereby, a plurality of yarn-feeding devices, means for independently rendering said yarn-feeding devices operative or inoperative, a yarn-clamping and cutting device including a supporting plate, a clamping finger for yieldingly clamping the yarns against said plate, and a stationary cutter for cutting the yarn between the clamping finger and the web, said supporting plate having a slot formed therein in which the yarn is drawn when thrown into action, whereby said yarn may be drawn from the clamping finger by a movement in the same direction in which the yarn is placed underneath said clamping finger, and the yarn drawn from the cutter in the opposite direction to that in which the yarn was drawn against said cutter.

17. In a knitting machine, the combination of a rotary and reciprocating needle cylinder, a series of short butt needles, a series of long butt needles, means for feeding a yarn to all of said needles, means for feeding an auxiliary splicing yarn to said short butt needles only, from a point substantially on the opposite side of the axis of the cylinder from the knitting point, a cam for depressing the long butt needles to miss the auxiliary splicing yarn, a lifting cam for the long butt needles during reciprocatory knitting to raise them to idle position, a depressing cam to move the long butt needles to active position, means for operating the said cams in opposite directions, the auxiliary splicing yarn guide being moved to active position when the machine is on circular work and when the lifting cam for the long butt needles is in inactive position, substantially as described.

18. A knitting machine having a series of needles and automatic means for knitting thereon from a body yarn a predetermined extent of fabric, in combination with means operating wholly at one side of the series

- of needles by relative movement between said means and series for placing on some of the needles at predetermined times in the operation prior to knitting on them a wrapping of an additional yarn. 5
19. A knitting machine having in combination a needle carrier and needles therein, a needle advancing cam surface and a stitch cam provided with a needle retracting surface and a main yarn feeding device, a device for feeding auxiliary yarn, means to position said auxiliary yarn feeding device operatively, and means co-operating with the needles during round and round knitting to cause the needles of a predetermined segment to take a different path between their advance at said needle-advancing surface and their retraction by said stitch cams with relation to the yarn from 10 said auxiliary feeding device. 20
20. In a circular knitting machine, in combination with a needle cylinder and needles therein, stitch cams and yarn feeding devices for feeding all of the needles, a device 25 for feeding auxiliary yarn for sectional splicing, means for rendering said device active and inactive at predetermined times and means co-operating with the needles to position a segment of them only to take the 30 yarn from said device.
21. In a circular knitting machine the combination of yarn-changing yarn guides, an internal guide device for the yarn thrown out of work, and needles movable with respect to the yarn in a position to take yarn 35 from a guide in an operative position, in combination with an auxiliary yarn guide, an internal guide device for the yarn from said guide, and means to position some of the needles only to take yarn from the said auxiliary guide. 40
22. In a circular stocking knitting machine with a main yarn feed, means for splicing an area less than the full circumference of the stocking comprising a splicing 45 yarn finger movably mounted to be thrown to and from feeding position, long and short butt needles arranged respectively in half circles, and cam means for dividing the long and short butt needles to permit feeding the splicing yarn to the short butt needles only which also take the main yarn, the said movable splicing finger remaining in feeding position during round knitting and throughout the needle circle while the splicing area is being formed and being removed only after splicing of said area has been effected. 55
23. A knitting machine having a series of 60 needles, a body yarn-guide, a stitch-cam, in combination with means acting on the needles between passages of the stitch-cam to isolate one or more needles from the other needles, an auxiliary yarn feed guide adapted to feed an additional yarn to said isolated 65 needle or needles only, and means for rendering said auxiliary yarn-guide operative and inoperative at a point fixed in relation to said isolating means at predetermined times. 70
24. A knitting machine having yarn changing means operating at predetermined times in combination with a device for holding the ends of withdrawn yarns in position to cause them to be tightened by the motion 75 of reinserted yarns encountering said device. 25. A knitting machine having needles and yarn guide means for entering and withdrawing yarns in succession, in combination with a device for holding and tightening the ends of the yarns when withdrawn comprising means to form a bight in a reinserted yarn in contact with other held yarns, whereby when said reinserted yarn is withdrawn by relative motion between 80 said needles and holding device said other held yarns are tightened between said yarn-guide and said holding device. 26. In a circular knitting machine, the combination of a device for feeding auxiliary yarn, means for moving said device into operative position, to introduce thread to the needles, and to move said device to withdraw thread from position to be engaged by the needles; and means whereby during 85 round and round knitting a plurality of successive needles are caused to travel at different heights from other needles in relation to said device, at the points of such introduction or withdrawal. 90
27. In a knitting machine, the combination of a needle cylinder, a series of successive short butt needles and a series of successive long butt needles, means for feeding a yarn to all of said needles, and means for feeding an auxiliary yarn to said series of short butt needles only, from a point substantially on the opposite side of the axis of the cylinder from the knitting point. 100
28. In a knitting machine, the combination of a needle cylinder, a series of successive short butt needles and a series of successive long butt needles, means for feeding a yarn to all of said needles, and means for feeding an additional yarn to said series of short butt needles only, from a point substantially on the opposite side of the axis of the cylinder from the knitting point. 110
29. A knitting machine having in combination a needle carrier and needles therein, a needle advancing cam surface and a stitch cam having a needle retracting surface engaging all the needles during round and round knitting, a main yarn feeding device, a device for feeding auxiliary yarn, means to position said device operatively, and means cooperating with the needles during round and round knitting to cause the needles of a predetermined segment to take a different path from that of the remaining needles. 115 120 125 130

between their advance at said needle advancing surface and their retraction by said stitch cam.

30. A knitting machine having in combination a needle carrier and needle therein, stitch cams having needle advancing and needle retracting surfaces and a main yarn feeding device, a device for feeding auxiliary yarn, means to position said last mentioned device operatively, and means cooperating with the needles to cause the needles of a predetermined segment to take a different path from that of the other needles between their advance and retraction by said surfaces at said stitch cams with relation to the yarn from said device.

31. In a circular knitting machine, the combination of a device for feeding auxiliary yarn; means for moving said device into operative position, to introduce thread to the needles, and to move said device to withdraw thread from position to be engaged by the needles; a stitch cam operating all the needles during round and round knitting, and means whereby during round and round knitting a plurality of successive needles are caused to travel at different heights from other needles at the points of such introduction or withdrawal.

32. In a circular knitting machine, the combination of a stitch cam operating all of the needles during round and round knitting, a device for feeding auxiliary yarns; means for moving said device into operative position to introduce thread to the needles, and to move said device to withdraw thread from position to be engaged by the needles; and means whereby a plurality of successive needles are caused to travel at different heights from other needles in relation to said device, at the points of such introduction or withdrawal.

33. In a knitting machine, a needle cylinder and needles carried thereby, a stitch cam operating all the needles, means for feeding a body yarn to all the needles, said needles passing said yarn guide at a common level, means for feeding an auxiliary yarn at a different point from said first mentioned yarn feed, and means for positioning a selected number of needles at a level adapted to engage said auxiliary yarn and for positioning the remaining needles at a level adapted to pass underneath said auxiliary yarn, said means for feeding the auxiliary yarn being so positioned relative to the first mentioned selected number of needles that the auxiliary yarn is drawn into engagement with and partially about the shank of the first of said last mentioned needles, whereby the insertion of the auxiliary yarn at a definite point in the fabric is positively ensured.

34. In a knitting machine, a needle cylinder and needles carried thereby, a stitch

cam operating all the needles, means for feeding a body yarn to all the needles, during round and round knitting, a yarn guide for feeding an auxiliary yarn at a different point from said first mentioned yarn feed, means for moving said auxiliary yarn guide into and out of operative position for causing the auxiliary yarn to engage a selected needle, and for holding said yarn guide in fixed position while feeding yarn to said needle and a selected number of following needles during successive knitting rotations, means for positioning the remaining needles at a level whereby they pass underneath the auxiliary yarn, and means for returning said last mentioned needles to normal knitting position after passing the auxiliary yarn.

35. A knitting machine having a series of needles, a body yarn guide for feeding yarn to all the needles, a stitch cam operating all the needles, in combination with means acting on the needles between passages of the stitch cam to isolate one or more needles from the other needles, an auxiliary yarn feed guide adapted to feed an additional yarn to said isolated needle or needles only, and means for rendering said auxiliary yarn-guide operative and in operative at a point fixed in relation to said isolating means at predetermined times and for holding said yarn guide in fixed position while feeding yarn to said isolated needles during successive knitting rotations.

36. In a circular knitting machine, the combination of a device for feeding an auxiliary splicing yarn to splicing needles, means for moving said device into yarn feeding position during round and round knitting, a needle cylinder and needles therein, a stitch cam retracting all the needles during round and round knitting, needle jacks having long butts associated with a succession of needles and needle jacks having short butts associated with the remaining needles, and a cam positioned in engaging relation to said long butts and in non-engaging relation to said short butts, to cause the splicing needles only to pass the auxiliary yarn at the level to take said yarn from said auxiliary yarn feeding device when in the operative position, prior to retraction of the needles by the stitch cam.

37. In a circular knitting machine, the combination of needle separating means for positioning a predetermined number of needles at a different level from that of the remaining splicing needles, a retracting stitch cam engaging all the needles during round and round knitting, a device for feeding an auxiliary splicing yarn located between said separating means and said stitch cam at a point substantially removed from said stitch cam, and means for positioning said feeding device during round and round knitting

at an operative level to feed yarn to the splicing needles and to position said yarn above the remaining needles at the needle levels determined by said separating cam.

38. In a circular knitting machine, the combination of a needle cylinder, a series of successive short butt needles and a series of successive long butt needles, means for feeding a yarn to all of said needles during 10 round and round knitting, a stitch cam operating all the needles during such knitting, means for feeding an auxiliary splicing yarn to needles in only one of said series at a point substantially removed from the stitch cam, means interposed to move said needles to a level to encounter said stitch cam after receiving said splicing yarn, and means in advance of said splicing yarn to cause predetermined needles to pass said yarn at a 20 different level from that of the remaining needles.

39. In a circular knitting machine, the combination of a needle cylinder and needles therein, a stitch cam for operating all the 25 needles during round and round knitting, devices for feeding a body yarn to all of the needles, a device for feeding an auxiliary yarn for sectional splicing, means for positioning said device at an operative level at 30 predetermined times, and a cam acting on the needle butts to position the needles in a predetermined segment at a level below said splicing yarn, said cam being located in non-engaging relation to the remaining 35 needles passing it at a level adapted to take said splicing yarn.

40. In a circular knitting machine, the combination of a needle cylinder and needles therein, a stitch cam for operating all the 40 needles during round and round knitting, devices for feeding a body yarn to all of the needles, a device for feeding an auxiliary yarn for sectional splicing, means for positioning said device at an operative level at 45 predetermined times, a cam surface raising all of the needles to a common level after their retraction by said stitch cam, the needles at said level being adapted to take yarn from said splicing device in the active position, a cam acting only on the needles of a predetermined segment to position them at 50 a level not to take said splicing yarn.

41. In a circular knitting machine, the combination of a needle cylinder and needles 55 therein, a stitch cam for operating all the needles during round and round knitting, devices for feeding a body yarn to all of the needles, a device for feeding an auxiliary yarn for sectional splicing, means for positioning said device at an operative level at 60 predetermined times, a cam surface raising all of the needles to a common level after their retraction by said stitch cam, the needles at said level being adapted to take yarn from said splicing device in the active posi-

tion, a cam acting only on the needles in a predetermined segment to retract them to a level below said splicing yarn.

42. In a circular knitting machine, the combination of a needle cylinder and needles 70 therein, a stitch cam for operating all the needles during round and round knitting, devices for feeding a body yarn to all of the needles, a device for feeding an auxiliary 75 yarn for sectional splicing, means for positioning said device at an operative level at predetermined times, a cam surface raising all of the needles to a common level after their retraction by said stitch cam, the needles at said level being adapted to take yarn 80 from said splicing device in the active position, a cam acting only on the needles in a predetermined segment to retract them to a level below said splicing yarn, and a cam 85 surface to position all of the needles at a common level prior to their retraction by said stitch cam.

43. In a knitting machine, a needle cylinder, a series of needles carried thereby, a 90 stitch cam operating all the needles, means for feeding yarn to all the needles during round and round knitting, said needles passing said yarn feeding means at a common level, means for feeding an auxiliary yarn at a different point from said first mentioned 95 yarn feed, and means for positioning a selected group of needles at a level to engage said auxiliary yarn and for positioning another selected group of needles at a level to pass underneath said auxiliary yarn, said 100 means for feeding the auxiliary yarn being so positioned relative to the first mentioned selected group of needles that the auxiliary yarn is drawn into engagement with and partially about the shank of the leading 105 needle of said group, whereby the insertion of the auxiliary yarn at a definite point in the fabric is positively insured.

44. In a knitting machine, the combination of a needle cylinder, a series of short 110 butt needles, a series of long butt needles, means for feeding a yarn to all said needles during round and round knitting, and means for feeding an auxiliary yarn during such knitting to said short butt needles only 115 from a point substantially on the opposite side of the axis of the cylinder from the knitting point.

45. In a knitting machine, the combination of a needle cylinder, a series of short 120 butt needles, a series of long butt needles, means for feeding a yarn to all said needles, means for feeding an auxiliary yarn during round and round knitting to said short butt needles only from a point substantially on 125 the opposite side of the axis of the cylinder from the knitting point, a cam for depressing the long butt needles, whereby said auxiliary yarn is drawn around the shank of the first needle in short butt series and pressed 130

- against the outer face of the short butt needles, and means for raising the long butt needles after said auxiliary yarn has been drawn around the shank of the last needle 50
5. of the short butt series and between said needle and the first needle in the long butt series.
46. A knitting machine having in combination a needle carrier and needles therein, 10 stitch cams having needle advancing and needle retracting surfaces, a main yarn feeding device, a device for feeding auxiliary yarn, means to position said auxiliary yarn feeding device operatively, and means to cause the needles of a predetermined segment to take a different path between their advance and their retraction by said surfaces of said stitch cams with relation to the yarn from said auxiliary yarn feeding device. 15
- 20 47. In a circular knitting machine, in combination with a needle cylinder and needles therein, a stitch cam for operating all the needles during round and round knitting, a yarn feeding device for feeding all of the 25 needles, a device for feeding auxiliary yarn for sectional splicing, means for rendering said device active and inactive at predetermined times, and means to position a segment of the needles only to take the yarn from said auxiliary yarn feeding device. 30
48. In a knitting machine, a needle cylinder, a series of needles therein, means for actuating the needles, yarn feeding means including a device for feeding auxiliary 35 yarn for sectional splicing, means for rendering said device active or inactive at predetermined times, and means to position certain needles differently from others during predetermined courses of round and round 40 knitting for forming a sectional splice.
49. In a knitting machine, a circular series of needles, means for feeding a main yarn to all the needles during round and round knitting, a splicing yarn guide movable into and 45 out of active position, means to divide the needles during round and round knitting to cause some of them to take the splicing yarn for forming a spliced area of less extent than the full circumference of the tube, said splicings yarn guide remaining in feeding position for course after course until after the completion of the spliced area. 50
50. In a circular knitting machine, in combination with a needle cylinder and needles therein, a stitch cam for operating all the needles during round and round knitting, a 55 yarn feeding device for feeding all the needles, a device for feeding auxiliary yarn for sectional splicing, means for rendering said device active and inactive at predetermined times, and means to position a segment of the needles only to take the yarn from said auxiliary yarn feeding device. 60
51. In a knitting machine, the combination of a cylinder with needles, a main yarn feed to continuously supply all the needles, an auxiliary yarn feed at a point remote from the main yarn feed, and means to control the needles at the region of the auxiliary feed so that auxiliary yarn is supplied only to certain predetermined needles. 65
52. In a knitting machine the combination of a cylinder with needles, a main yarn feed to continuously supply all the needles, an auxiliary yarn feed at a point remote from the main yarn feed, and cams operative at the region of the auxiliary yarn feed to effect a subdivision as between the needles whereby the auxiliary yarn is supplied only to a certain predetermined group of them. 70 80
53. In a knitting machine the combination of a cylinder with needles, an auxiliary yarn feed adapted to remain in operating position only during predetermined revolutions in round and round knitting, means to actuate the needles at the knitting point to draw fabric loops, and means whereby the auxiliary yarn is wrapped about predetermined needles in advance of the knitting point for subsequent inter-knitting with a 85 main yarn fed to all the needles at said knitting point. 90

In testimony whereof, I have hereunto signed my name at Philadelphia, Pennsylvania, this twenty-first day of October, 1912.

ALBERT M. PIGEON.
